Application December 13, 1937, Serial No. 179,442

4 Claims. (CL 209—458)

An object of our invention is to provide a novel system and mechanism for the separation of gold and other valuable metals from the alluvial deposits in which they occur, hydraulically.

5 A still further object is to provide a more efficient system of mining in which the metal particles existing in alluvial and other like matrix may be carried by moving water into sump holes and then pumped, or pumped directly from the 10 beds of streams, by one or more centrifugal pumps through a separator casing containing diffusing vanes and riffles which cause the gold to be deposited while the debris or tailing is carried through and discharged at a desired location.

15 A still further object is to provide a novel form of ore separator in which a series of diffusing vanes and riffles are employed to separate the valuable metal from the alluvial deposit.

20 A further object is to provide an enclosed casing about the separating members which scour and remove the metal and in which casing the metal is retained after its separation whereby access thereto by unauthorized persons and theft of the metal is prevented.

25 A still further object is to provide a separating apparatus which is inexpensive to construct, compact and of relatively small weight so that it is portable and may easily be transported to any inaccessible location which is rich in mineral 30 deposits. Other and further objects will become apparent to those skilled in the art as the description of the invention proceeds. For a better understanding thereof, reference is made to the following description taken in connection with 35 the accompanying drawings in which;

Fig. 1 is an elevation of the separator also showing the pump connected thereto,

Fig. 2 is a sectional view through the separator taken in a plane normal to its length,

40 Fig. 3 is a vertical section of the inlet conduit,

Fig. 4 is a horizontal section of the approach conduit,

Fig. 5 is an enlarged sectional view of the riffle and baffle plates taken in a vertical plane passing 45 through the axis of the separator and,

Fig. 6 is a sectional view showing the shape of casing used in the construction of the centrifugal pump.

Referring first to Fig. 1, our invention is shown 50 as comprising an alluvial separator 1 shown as a steel conduit of generally cylindrical shape and preferably made of three or more sections 2, each 4 feet long and electrically welded, flanged or riveted together at the joints 3. The separator 55 is mounted for easy rotation on two pairs of roll-

ers 4, the rollers being mounted on a pair of skids 5. This mounting arrangement makes the separator readily portable and easy to transport as a single unit or in sections and the cost of removal from one site to another very small. Running along the upper half of the conduit and electrically welded to the inner wall thereof is a flat steel plate 6 which carries a series of flat steel deflecting or baffle plates 7 about 2 inches wide and each inclined at an angle of about 45 degrees to plate 6 as shown more clearly in Fig. 5. This construction results in a closed space being formed between plate 6 and the top of the conduit. Electrically welded to the inside of the conduit and running parallel to plate 6 are two 15 steel retaining strips 8 which serve to hold the riffles 9 in position and which extend clear along the sides of the conduit.

Each riffle is preferably made of cast iron and comprises a substantially flat body portion 10 20 whose lower edge is curved to fit closely against the interior of the conduit and whose upper edge is straight. Projecting from the rear of body portion 10, and at right angles thereto, are two spacer webs 11 which are shaped as shown in 25 Fig. 5 so that the rear, inclined edge 12 of each spacer web rests against the front face of the adjacent riffle. This construction serves to space the riffles 6 inches apart and to maintain them at an angle of approximately 45 degrees with respect to the shell 1, as shown more clearly in 30 Fig. 5. If desired, a wear plate 13 may be provided along each side of the shell, those shown consisting of long steel plates, 5 inches wide and having their lower and upper edges electrically 35 welded to strips 8 and the inner surface of the conduit respectively. The function of these plates is to prevent wear on the interior surface of the conduit, the tailings striking and rubbing against the wear plates as they pass along 40 through the conduit. Additional riffles may be secured to the wear plates, if desired.

An outlet conduit 14 and an inlet conduit 15 are provided and secured in place at the two ends of the separator, the cross sectional areas 45 of these conduits being substantially smaller than that of the separator, so that the velocity of the fluid is decreased considerably upon its entering the separator and it is increased again upon its entrance into the outlet conduit. The construction of conduits 14 and 15 is similar except that no deflecting plates are provided in outlet 14. As shown, conduit 15 terminates in a flange 16, which abuts against a flange 17 on the end of the separator and is secured thereto by a plu- 55

- rality of bolts 50. Flange 16 has a rectangular shaped opening 18, 20 inches wide and 11 inches high. Welded to flange 16 at the edges of this opening are the top and bottom walls 19 and 20 5 and side walls 21 and 22 of a generally rectangular shaped box, the sides of which are tapered toward the right to form an opening 8 inches square. The four sides of this box may be reinforced by having a plurality of thin steel strips 23 welded thereto at spaced intervals, as shown in Fig. 3. At its small end the box has a circular steel flange plate 24 welded thereto, plate 24 co-operating with a flange 25 to form a rotary joint of any known type, the details of which are not 10 shown. Flange 25 is secured to the outlet pipe 26 of the centrifugal pump 27, the pump in this case having an outlet pipe 8 inches in diameter. Welded to the plates 21 and 22 are the spaced apart baffle or deflecting plates 28 arranged at 15 an angle of approximately 45 degrees and extending the full width of plates 21 and 22. Baffle plates 28 are staggered along the sides 21 and 22, being located at the intersections of the sides and the dash line 55 as shown in Fig. 4.
- 25 In order to remove the recovered metal from the separator, an opening is made in flange 16 and plate 22 and a short section of steel pipe 29 has one end cut to fit this opening and is electrically welded in the position shown in Fig. 4. 30 The outer end of pipe 29 has a circular annular flange 30 welded thereto and a suitable cover plate 31 secured to 30 as by a plurality of bolts 32 or other known fastening means. With cover plate 31 in position, it will be understood that 35 water cannot escape from or through cleanout pipe 29 and any recovered metal which may be in the separator is completely enclosed and may not be easily stolen as is the case when the usual type of open riffle troughs are used.
- 40 According to our invention the alluvial deposit bearing the precious metal, for example, gold, platinum or tin in the form of powder and fine and larger sized fragments, is washed down one or more ditches 34 into a sump hole 35 into 45 which the intake hose or pipe 36 of the centrifugal pump projects, power being supplied to the pump by an electric motor or equivalent power source. The outlet orifice of the pump is preferably connected to the short pipe 26 by a strong 50 rubber hose 33 to provide a degree of flexibility at the inlet of the separator. The mixture of water and alluvial deposit is drawn up by the pump and discharged at a high velocity, for example, 10 to 20 feet per second through the outlet pipe 26 into the small end of inlet conduit 55 15. As the mixture passes through conduit 15, its velocity decreases steadily and the matrix is caused to strike against the sides thereof by the baffle plates 28, many of its particles also 60 striking these plates. This action washes and scours the matrix particles and is effective in washing away the film of dirt which encloses many of the particles of metal. This removal of the lighter material adhering to the metallic 65 particles assists in the later separation and recovery of the latter in the separator.
- The effective area of the separator being substantially greater than that of conduit 15, the 70 velocity of the mixture is further reduced in the separator to from 5 to 10 feet per second, a velocity of flow of 5.5 feet per second through the separator having been found very effective. As the mixture passes along through the separator the heavy metal particles settle down in the 75 spaces between the riffles 9 under the action of

gravity, their specific gravity being much higher than unity. Downwardly directed currents and increased turbulence caused by the baffle plates 7 also carry the metal particles into the spaces between the riffles 9. According to our invention 5 a still third and novel action causes the metal particles to settle into the areas of least disturbance which are located just at the rear of flat plates 10. Such an area is indicated in Fig. 5 by 37. Consider a metal particle on the 10 front face of plate 10. Gravity will not only cause it to pass down to the bottom of this plate and onto the interior surface 38 of the bottom of the separator, but also cause it to move forward along surface 38 into the quiet area 37, 15 since the inclination of the separator and surface 38 is in this direction. In other words gravity assists in moving the heavy metal particles into the portions of the stream where the least disturbance exists. We prefer to operate the 20 separator inclined upwards at an angle of from 5 to 30 degrees in order to secure this extra beneficial action from the force of gravity but it will be understood that the invention is not so limited and our improved separator may be operated in a level or declining position. With the separator inclined upwardly at an angle of substantially 10 degrees, it was found that substantially all the metal settled within the first 25 six feet at the inlet end, so that a separator 30 made up of three sections, each four feet long, is sufficient for certain types of alluvial deposit. For other deposits and metals we may, however, provide an additional number of sections as required. 35

As the metal accumulates in the spaces between the riffles, it displaces any sand or gravel therein and forces them upwards into the rapidly moving stream, which carries them along toward the outlet. Gravel and stones are prevented 40 from piling up into mounds between the riffles, since such mounds projecting into the separator would decrease its effective cross sectional area and hence increase the velocity of fluid flow therethrough. This increased velocity will carry 45 the projecting stones onward toward the outlet. Upon reaching the outlet conduit 14 the velocity of the stream again increases as it passes therethrough and in the discharge pipe 39 the same 50 velocity as in the inlet pipe 26 is reached. The residue may be discharged into a desired site directly from pipe 39 or it may be conveyed to a site at a distant location through a pipe line in which one or more booster pumps may be connected to maintain a high velocity of flow. 55

After operation for a desired period such as 24 hours, and a quantity of metal is in the separator, this may be easily removed by rotating it 180 degrees when the debris and metal will fall onto plate 6 and the debris will be washed out 60 by the stream of water from the pump. This cleaning out process may be repeated, if required. The separator is then rotated another 90 degrees into such position that pipe 28 is at its lowest position. Cover plate 31 is then removed and a stream of water played into the separator from a hose or pipe inserted into pipe 39 when the recovered metal will be washed out 65 from between the riffles and pass down the smooth interior surface of the separator into pipe 70 29 where it is discharged. In this washing out of the recovered metal, the inclination of the separator towards the inlet end, assists greatly in its transfer through the separator.

Any suitable means, either hand or power op- 75

erated, may be used to rotate the separator on the rollers 4. That shown in Fig. 2 comprises a winch or capstan 41 mounted in bearings on a supporting block or pedestal 40 secured to an 5 extension of one of the skids 5. A flexible cable or belt 43 has several turns passed around the winch drum and one or more turns passed around the separator. A suitable crank or handle 42 serves to rotate the winch. Or, a spur 10 gear and pinion drive may be used instead.

In order to permit ready inspection of the amount of recovered metal in the separator at any time, a section thereof extending over 90 degrees or more may be cut out of the bottom near 15 the inlet end and replaced by a similar shaped plate of glass or other transparent material. Such a glass window is indicated at 44, suitable known fastening means (not shown) being employed to secure the window in position. Also 20 instead of, or in addition to the riffles heretofore described, a series of poles or steel rails may extend along the separator in the direction of its length.

As shown in Fig. 6, the impeller 46 of the centrifugal pump 27 rotates within a casing or shell whose inlet is at 48, the outlet not being shown. As clearly shown, the cross section formed by the outer ring 49 and sides 47 of the shell, is rectangular in shape.

30 As compared to other systems of mining, our system presents the following advantages:

1. It makes commercially valuable large areas of alluvial deposits which were valueless heretofore.

35 2. It renders the separator readily portable.

3. It makes possible the separation of gold and other valuable metals when a pump of the correct shape is used. The rectangular shaped pump shell throws the water and matrix mixture out radially in a straight stream, whereas a pump having the usual arch shaped shell, causes a spiral motion from each side of the pump toward the top of the arch causing the heavier solid bodies to strike against each other 40 and thus reduce the velocity of flow.

45 4. It reduces very substantially the cost of the riffing outfit.

5. It makes it possible to mine the matrix, separate the metals from it and discharge the 50 matrix residue at almost any desired location and all in one continuous operation by means of centrifugal pumping.

6. It scrubs and cleanses the desired metal by the rapidly moving water and by contact of the 55 particles with the rapidly moving impeller blades of the pump, the baffle plates of the inlet conduit and separator and also the riffles.

7. It keeps the recovered metal enclosed, thus protecting it against theft.

60 8. It makes it possible to carry the debris to almost any desired location by installing one or more booster pumps in the outlet pipe, if one pump does not carry it far enough.

9. It makes possible the easy inspection of the 65 recovered metals through the transparent section or sections in the bottom of the separator.

10. It saves time and much labor, increasing production to a marked degree and thereby greatly decreasing the cost of mining.

70 11. It provides an easy and quick means for cleaning out the separator hydraulically and also for removing the recovered metals therefrom.

12. Its circular shaped casing is much more portable than the present flat trough riffle boxes and the recovered metals are much more easily gathered from it.

13. It does not require the pumping of the 5 matrix to a high elevation from which it runs over the riffles by gravity, thereby effecting a large saving in power and cost of equipment.

14. It provides a forced riffle action in a confined space whereby clogging up of the riffles with 10 matrix residue is prevented and a complete recovery of the metals in a short length of separator is possible.

15. It makes frequent, periodic removal of the recovered metals easy and inexpensive whereby 15 accurate information as to their value is available at all times.

While we have indicated and described an arrangement for carrying our invention into effect, it will be apparent to one skilled in the art 20 that the invention is by no means limited to the particular organization shown and described, but that many modifications may be employed without departing from the scope of the invention as set forth in the following claims. 25

We claim:

1. A mineral separator comprising in combination, a substantially long, cylindrical casing having inlet and outlet openings at its opposite ends, a horizontal plate extending lengthwise 30 within said casing and secured to the walls thereof at its opposite sides, a plurality of downwardly directed baffle plates extending crosswise of said casing and secured to the bottom of said plate at spaced apart points, and a plurality of riffles 35 arranged at spaced apart points along the bottom of said casing, each of said riffles comprising a substantially plane plate having its lower edge shaped to conform to the interior surface of said casing and its upper edge substantially 40 straight.

2. The arrangement of claim 1 in which each riffle plate is provided with two offset portions arranged at substantially 90 degrees thereto and adapted to engage the next adjacent riffle plate 45 and thereby insure the desired spacing apart of the riffle plates.

3. A mineral separator comprising in combination, a closed casing having a curved bottom wall and being provided with inlet and outlet openings 50 at its opposite ends, and a series of riffles disposed along the bottom of said casing, each riffle comprising a substantially flat plate whose lower edge is curved to conform to the bottom wall of the casing and a plurality of spacer webs 55 projecting from the rear surface of said flat plate and whose rear ends are inclined so as to seat against the front face of the next adjacent riffle and maintain the flat plates of the series of riffles in spaced apart, parallel relation. 60

4. The combination as set forth in claim 3 in which said casing is formed of metal and in which oppositely disposed rods are secured to the interior wall of the casing with the lower edges of the rods in engagement with the ends 65 of the flat riffle plates whereby said rods maintain the riffles in position within said casing.
